UNITED STATES PATENT OFFICE.

PERCY C. AVERY, OF CHICAGO, ILLINOIS.

ACETYLENE-GAS GENERATOR.

SPECIFICATION forming part of Letters Patent No. 760,723, dated May 24, 1904.

Application filed December 15, 1900. Renewed April 2, 1904. Serial No. 201,292. (No model.)

To all whom it may concern:

Be it known that I, PERCY C. AVERY, a citizen of the United States, residing at Chicago, in the county of Cook and State of Illinois, 5 have invented certain new and useful Improvements in Apparatus for Generating Gas, of which the following is a specification.

The present invention relates to that class of apparatuses in which the gas is generated by the bringing together of a solid and a liquid gas-producing substance—as, for example, the generation of acetylene by the bringing together of metallic carbid and water.

The principal object of the invention is to provide an apparatus having improved means for insuring the uniformity of the pressure of the gas generated without regard to the quantity being generated.

A further object of the invention is to provide improved means whereby the apparatus may be adjusted so that the pressure may be regulated in the first instance, the apparatus being so constructed that it thereafter operates automatically and without producing any material variation in the pressure.

The invention consists in the features of novelty that are hereinafter described, and in order that it may be fully understood I will describe it with reference to the accompanying drawings, which are made a part hereof, and in which—

Figure 1 is a sectional elevation of an apparatus embodying the invention in its preferred form. Fig. 2 is a horizontal section thereof. 35 Fig. 3 is a sectional elevation of an apparatus embodying some features of the invention under a slight modification. Fig. 4 is a horizontal section thereof.

A represents a receptacle adapted to contain 40 the water or other liquid gas-producing substance, which may be of any desired capacity, regard being had for the generating capacity of the apparatus. It is preferably in the form of a cylindrical tank open at the top, so as to maintain its interior at atmospheric pressure.

B is a receptacle, hereinafter called the "carbid-holder," which is adapted to contain 45 any desired quantity of carbid or other solid gas-producing substance up to the full capacity of the apparatus and which in practice does

contain the full quantity necessary to run the apparatus for the length of time it is desired to have it run before replenishing it.

The term "carbid-holder" as herein used is thus limited and does not comprehend a device onto which small quantities of carbid, taken from the carbid holder proper, are automatically discharged from time to time as the process of generation is carried on. This carbid-holder preferably consists of an inex- 55 tensible vessel of somewhat smaller diameter than the receptacle A, so that when placed within the receptacle an annular space α is left between them. The carbid-holder is movable bodily with relation to the water-recep- 60 tacle. It has a top which is closed save for a restricted gas-outlet b, with which communi- 65 cates a flexible tube C, through which the gas is led off, and it has a bottom which is closed save for means for admitting to its interior a 70 limited quantity of water. Preferably the top of the carbid-holder consists of a cap D, which rests upon the top of the side walls through the medium of an elastic packing d, the cap being preferably provided with an annular 75 flange d', which projects into the body of the holder. The cap is preferably held down gas- tight by means of a rod E, the lower end of which is secured to the bottom b' of the car- 80 bid-holder, whence it extends upward through an opening in the cap and receives a nut F, the upper end of the rod and nut being screw- threaded.

Instead of the above-described arrangement for holding the cap gas-tight, any other suitable arrangement may be used. In Fig. 3 I have shown it as being provided with a threaded flange d' engaging corresponding threads on the body of the holder.

Preferably the carbid-holder is made of 90 metal, and for the admission of water to its interior the bottom b' is provided with one or more restricted openings b'', so that when the receptacle A is filled with water to the proper level and the carbid-holder is inserted in the 95 receptacle, so as to be submerged in the wa- ter to a greater or less depth, there will be in the space α a hydrostatic column tending to force the water into the carbid-holder through the opening b''. I desire to have it under- 100

stood, however, that the invention is not limited to the material of which the carbid-holder is made, so long as it is capable of confining gas under pressure sufficient for the purposes 5 hereinbefore described or to the means for admitting the water to its interior further than that it should be of such character that water will tend to enter it when submerged. I have obtained good results by the use of a 10 carbid-holder made of porous material and without any perforations in the bottom, as shown in Fig. 3. Excepting for the restricted inlet for water the carbid-holder and water-receptacle are without internal communication 15 with each other, and this distinguishes the apparatus from that class of apparatus in which the gas upon leaving the generating-chamber is conducted into the bell of a gasometer by which the carbid-holder is supported, the bottom 20 of the bell being sealed by the water in the water-receptacle.

It is clear that when the carbid-holder containing a quantity of carbid and closed at top, except for the gas-outlet, is submerged 25 in water the gas generated within it will have a pressure substantially proportional to the height of the hydrostatic column in the annular space a . It follows, therefore, that if the carbid-holder and receptacle A were to 30 remain in unchanged relations to each other as the generation of gas proceeds the height of the hydrostatic column would diminish and the pressure of the gas within the carbid-holder would correspondingly diminish. To 35 prevent this, I provide the apparatus with means for maintaining the hydrostatic column at the same height, or practically so, regardless of the depth of the water or its surface-level in the receptacle A. The preferred means 40 for accomplishing this is a weight G, supported by a lever H upon one side of its fulcrum I, the carbid-holder being attached to the lever upon the other side of its fulcrum. This attachment may be accomplished by perforating 45 the nut F and the lever H and passing a pin h through the perforations, the pin being easily removable in order to enable the lever to be detached from the nut when it is desired to remove the latter. The weight G is adjust- 50 ably secured upon the lever by some suitable means—as, for example, a set-screw g —so that within certain prescribed limits it is possible to obtain any desired lifting effect upon the carbid-holder. Preferably it is so adjusted 55 that it counterbalances the weight of the uncharged carbid-holder, so that when the holder is charged and in position, as shown in Fig. 1, the hydrostatic column will be in proportion to the weight of the contents of the holder. 60 With the apparatus thus adjusted and charged as the generation of gas proceeds the level of the water in the receptacle A will gradually fall, and the carbid-holder, being yieldingly supported partly by the counterbalance- 65 weight and partly by its buoyancy, will fall

with it, so that notwithstanding these changes in the relations of the parts the bottom of the carbid-holder will be kept constantly submerged, and the height of the hydrostatic column, which determines the pressure of the 70 gas, will remain practically constant. It is true that as the generation proceeds the quantity of water in the residue within the carbid-holder (the bottom of the carbid-holder being open to the admission of water, but not to the escape of the residue) will gradually increase and somewhat increase the weight of the contents of the carbid-holder, thereby correspondingly increasing the height of the hydrostatic column; but this is not only not objectionable, but, on the contrary, desirable, because the moist residue will tend to retard the upward flow of the water to the dry carbid, and hence a corresponding increase in the pressure of the water is necessary in order to maintain the uniformity in the pressure of the gas. 80

Instead of using a weight I may yieldingly support the carbid-holder by means of a spring G', placed within the receptacle A. In this case the carbid-holder is provided with wings 90 b^3 for preventing it from tipping.

Where the apparatus is used on a portable conveyance—such as a vehicle, locomotive, or railway-car—the water in the receptacle A will be more or less agitated, and in order to 95 prevent it from disturbing the position of the carbid-holder I provide means for retarding the up-and-down movement of the latter. This means may consist of a flange K, carried by the carbid-holder and nearly equal in diameter to the internal diameter of the receptacle A, leaving between them only a small annular space through which the water can pass. This will act like a dash-pot and positively prevent disturbing the relations of the parts under the conditions named. 100

It is to be understood that the terms "water" and "carbid" as used in this specification are intended to include, respectively, any liquid and solid gas-producing substances 110 which when introduced will generate gas.

The apparatus which forms the subject of the present application does not belong to that class in which a carbid-holder consisting of an open basket or similar receptacle is contained within a float, which is completely open at bottom and dips into a body of water so that the float will rise and fall as the pressure within it increases and decreases and in doing so alternately lift the carbid-holder entirely 120 above the surface of the water and lower it so that it will be submerged to a greater or less extent. In the apparatus which forms the subject of the present application the spring or weight produces an invariable upward pressure upon the carbid-holder, whereby it is yieldingly supported with its bottom (meaning thereby the support for the body of carbid) constantly submerged to such a depth 125 that the level of the water will be above the 130

level of the area of reaction, (meaning thereby the area or region throughout which the damp residue and dry carbid have contact with each other and at which the generation principally takes place,) so that said holder being closed at top, save for a gas-outlet, and also at bottom, save for the restricted inlet, the pressure of the gas within it will react upon the top and bottom equally, or substantially so, and not upon the surface of the water in the water-receptacle. Because of this substantially equal reaction the gas-pressure has no tendency to lift the carbid-holder out of the water. There is no alternate up-and-down movement of either the holder or the water-level, the movement of both being always downward.

What I claim as new, and desire to secure by Letters Patent, is—

- 20 1. In an apparatus for generating gas, the combination of a water-receptacle, a carbid-holder located within and movable bodily relatively to the water-receptacle, and means for exerting an invariable upward pressure upon said carbid-holder whereby it is yieldingly supported with its bottom constantly submerged in the water contained in the water-receptacle and is allowed to fall as the level of the water falls, said carbid-holder having 25 an outlet for gas and a submerged restricted inlet for water, said water-receptacle and carbid-holder being without internal communication excepting through said inlet, substantially as described.
- 30 2. In an apparatus for generating gas, the combination of a receptacle for water, a carbid-holder located within and movable bodily relatively to the water-receptacle and means for exerting an invariable upward pressure upon said carbid-holder whereby it is yieldingly supported with its bottom constantly submerged in the water contained in the water-receptacle and is allowed to fall as the level of the water falls, said carbid-holder being gas-tight save for an outlet for gas and a submerged restricted inlet for the water, the water-receptacle and carbid-holder being without internal communication excepting through said inlet, substantially as described.
- 35 3. In an apparatus for generating gas, the combination of a receptacle for water, an extensible carbid-holder adapted to contain a full charge of carbid, said carbid-holder being within the water-receptacle and movable relatively thereto, means for yieldingly supporting the carbid-holder with its bottom constantly submerged in the water contained in the water-receptacle, said carbid-holder having a restricted outlet for gas and having 40 means for admitting water through its submerged portion and being adapted to confine gas under sufficient pressure to regulate the admission of water to its interior and thereby maintain a hydrostatic column outside of it substantially as set forth.

4. In an apparatus for generating gas, the combination of a receptacle for water, a carbid-holder adapted to contain a full charge of carbid, said carbid-holder being within the water-receptacle and movable relatively thereto, and means for yieldingly counterbalancing the uncharged carbid-holder, said carbid-holder having a restricted outlet for gas and having means for admitting water through its submerged portion, and being otherwise 70 gas-tight, whereby its buoyancy sustains the weight of the charge of carbid substantially as described.

5. In an apparatus for generating gas, the combination of a receptacle for water, open to 80 atmosphere whereby atmospheric pressure is maintained within it, a carbid-holder adapted to contain a full charge of carbid, said carbid-holder being within the water-receptacle and movable relatively thereto, and means for 85 yieldingly supporting the carbid-holder with its bottom constantly submerged in the water contained in the water-receptacle, said carbid-holder having a restricted outlet for gas and having means for admitting water through its 90 submerged portion and being adapted to confine gas under pressure whereby its buoyancy assists in yieldingly supporting it and whereby the pressure of the gas within it regulates the admission of water to its interior and maintains a hydrostatic column outside of it substantially as described.

6. In an apparatus for generating gas, the combination of a receptacle for water, a carbid-holder therein, means for yieldingly supporting said holder with its lower portion constantly submerged, and a device operating after the manner of a dash-pot, for preventing the sudden movement of the holder, substantially as described.

7. In an apparatus for generating gas, the combination of a receptacle for water, a carbid-holder therein, means for yieldingly supporting said carbid-holder with its lower portion constantly submerged, and a flange carried by the carbid-holder and extending to within a short distance of the wall of the water-receptacle, substantially as described.

8. In an apparatus for generating gas, the combination of a receptacle for water, a carbid-holder adapted to contain a full charge of carbid, said carbid-holder being within the water-receptacle and movable relatively thereto, and a weight for yieldingly supporting the uncharged carbid-holder, the carbid-holder having a restricted outlet for gas and being adapted to confine gas under the pressure whereby its buoyancy will support the weight of the charge of carbid and whereby the carbid-holder will be yieldingly supported with its bottom constantly submerged in the water in the receptacle, the carbid-holder being provided with means for admitting water through its submerged portion substantially as described.

9. In an apparatus for generating gas, the combination of a receptacle for water, a buoyant carbide-holder adapted to contain a full charge of carbide, said carbide-holder being 5 within the receptacle and movable relatively thereto and having means for maintaining upon the outside of it and within the water-receptacle a hydrostatic column extending above the level of the area of reaction, and

means additional to its buoyancy for yielding- 10 supporting it and allowing it to fall as the level of the water falls, substantially as described.
